UNITED STATES PATENT OFFICE.

FRED H. ROOT, OF JAMESTOWN, NEW YORK.

GLOBE-ADAPTER.

1,179,221.

Specification of Letters Patent.

Patented Apr. 11, 1916.

Application filed September 10, 1915. Serial No. 50,026.

To all whom it may concern:

Be it known that I, FRED H. Root, a citizen of the United States, residing at Jamestown, in the county of Chautauqua and State 5 of New York, have invented new and useful Improvements in Globe-Adapters, of which the following is a specification.

This invention relates to globe adapters and the principal object of the invention is 10 to provide a simple, efficient and inexpensive device of this character whereby short length chimneys may be readily used in lanterns.

Further objects of this invention will appear as the following specific description is 15 read in connection with the accompanying drawing which forms a part of this application, and in which:—

Figure 1 is an elevation showing the device applied to a lantern of the ordinary 20 type. Fig. 2 is an elevation of the adapter removed from the lamp. Fig. 3 is a vertical sectional view taken therethrough.

Referring more particularly to the drawing, 1 represents the head or globe receiving 25 sleeve of an ordinary lantern, 2 the chimney or globe and 3 generally indicates the adapter.

This adapter comprises an annular body 4 constructed of any suitable material such 30 as sheet metal, preferably having a resilient quality. At the base of the body, the same is outwardly flared to form a globe receiving flange 5 and at the upper end of the body a plurality of sleeve engaging fingers or projections 6 are formed. These fingers are 35 preferably slightly deflected at their upper ends so as to properly engage the sleeve 1 and hold the adapter in position therein. Immediately below the finger 7 a limiting 40 shoulder 8 is produced in any suitable manner and this shoulder engages the sleeve or head 1 thus limiting the inward movement of the adapter into said sleeve.

The body is provided with an annular 45 series of apertures 8' arranged immediately beneath the shoulder 5 so as to afford an exit for excess heat within the chimney or adapter. When the adapter is removed

from the lantern, the ordinary or full length chimney or globe may be employed engaging 50 the sleeve in the usual manner. By applying the adapter, a short or half length globe may be readily used, the flange 5 taking the place of the sleeve or head and receiving the upper end of the globe in the usual manner. 55 These short length globes have the advantage of reducing the cost of the chimney approximately half and are also much more readily cleaned than the full length globes. Furthermore, it will be found that with the 60 use of the short globe, they will stay clean longer than the full length globe as the soot from the lantern usually collects upon the upper portion of the globe and as the adapter is not transparent, it is not necessary 65 to clean the same as often as where the full length globe is used. As shown, the adapter is slightly corrugated circumferentially so as to relieve the monotony and is also gradually tapered from its lower end to 70 the shoulder 8.

What is claimed is:—

1. A globe adapter for lanterns comprising a tubular metallic body having a flared lower end arranged to receive the upper end 75 of the chimney or globe, a plurality of spaced fingers formed at the upper end of the body, and limiting means arranged at the base of said fingers, said body having a plurality of vent openings adjacent the limiting means. 80

2. A globe adapter of the character described, comprising a tubular metallic body having a flared lower end arranged to receive a globe or chimney, spaced outwardly diverging fingers formed at the upper end 85 of the body by cutting away a portion of the body, and a shoulder arranged below the fingers and adapted to engage the top of the lantern, said body having vent apertures adjacent the shoulder. 90

In testimony whereof I affix my signature in presence of two witnesses.

FRED H. ROOT.

Witnesses:

CLYDE ROOT,
OLIN M. SPENCER.
